UNITED STATES PATENT OFFICE

2,515,977

FORM APPARATUS FOR WALL OPENINGS

Joseph Banneyer, Chicago, Ill.

Application May 26, 1948, Serial No. 29,293

5 Claims. (Cl. 25—131)

1

This invention relates to form apparatus for wall openings. The invention is particularly useful in the construction of concrete walls, etc. and in the forming of window frames, door frames, and other frames for wall openings.

An object of the invention is to provide form apparatus which may be brought together for quick assembly and disassembly and employed for the forming of wall-opening frames in wall openings, such as, for example, window and door openings, etc. Still another object is to provide form apparatus readily applied to wall-form openings for closing the space between the walls and for supporting wall-opening frames and for adjustably supporting said frames within the wall space. A still further object is to provide, in combination with panel structure for forming walls and having openings therein, form apparatus for sealing the space between the walls about said openings and for receiving the wall-opening frames, means being provided for adjustably supporting said frames within the area to be filled by concrete, etc. Other specific objects and advantages will appear as the specification proceeds.

The invention is illustrated, in preferred embodiments, by the accompanying drawing, in which—

Figure 1 is a side view in elevation of form apparatus embodying my invention; Fig. 2, an enlarged broken view in elevation of a portion of a window frame to be secured within a concrete wall, etc.; Fig. 3, a broken side view in elevation of a portion of a door frame or jamb; Fig. 4, a transverse sectional view of a portion of the wall-form structure about the concrete wall and showing the form mechanism for supporting a window frame within the concrete wall, etc.; and Fig. 5, the concrete wall equipped with the window frame, the form apparatus having been removed.

In the illustration given, 10 designates a number of panels formed of steel, aluminum, or other suitable materials, having outwardly-extending flanges 11, equipped with inwardly-turned ledges 12. The flanges 11 may be secured together by C clamps 13 to form spaced partition walls. A detailed disclosure of the panels 10, flanges 11 and various types of clamps 13 by which the flanges are secured together, is set out in my co-pending application, Serial No. 29,294 for Form Apparatus, filed May 26, 1948. That application also sets out clamp and brace structure by which the walls are supported.

For the practice of the present invention, it

2

will be understood that any suitable form apparatus may be employed for the forming of the spaced walls between which the concrete is to be poured.

5 The wall-form structure illustrated leaves on one side an opening indicated by the numeral 14, which is adapted for use as a window opening, and another opening 15, which is adapted for use as a door opening.

10 In forming the window opening 14, as shown more clearly in Fig. 4, the adjacent panels 10 terminate in outwardly-extending flanges 11. Abutting the flange 11 on each wall is a form member 16. The form member 16 has an outwardly-extending flange resting against flange 11 and a rearwardly-extending ledge parallel with ledge 12. Each form 16 extends inwardly, and then is turned sharply to the rear to provide a guide wall 18. The two guide walls 18 of the two members 16, as shown more clearly in Fig. 4, provide between them a channel 19, in which is mounted the form frame 20. The form frame 20 is fixed to the channel walls 18 by means of bolts 21.

15 20 Any suitable means for securing the flanges of form members 16 to the panel flanges 11 may be provided. As shown more clearly in Fig. 4, C clamps 13 may be employed for this purpose.

The frame members 20 are provided, at spaced 25 intervals, with guide projections 22, also enclosed within the channel walls 18. Guided between the members 22 and between the channel walls 18 are the shoes 23. Shoes 23 may be provided, if desired, with grooves 24 adapted to receive the tongues 25 of the window frames 26. The window frames 26 may be provided with inwardly-extending tie members 27 formed of waved metal strips, or the like.

30 35 To support the shoes 23 adjustably against the window frames 26, a bolt 28 may be extended through the frame 20 in threaded relation therewith and may bear within a recess in the shoe 23. If desired, a ring 29 may be provided for locking the end of the screw within the recess of the shoe 23.

40 45 To advance or retract the shoe, the bolt 28 may be turned, and for this purpose, the bolt is provided with a head 30. It will be understood that other equivalent means may be employed for this purpose.

50 For closing the space between the walls forming the door opening 15, I provide a similar frame structure 31 of the shape suitable for a door frame and equipped also with tie members 32, as shown more clearly in Fig. 3. I provide forms

16a similar to form 16 and providing a similar channel receiving the door frame 31. Within the channels are mounted shoes 33 which engage the side frames or jambs of the door and are supported by means of a turn-buckle 34. The shoes may be located at the extreme ends of the openings in the frame 16a so as to support the top and bottom frame portions, as well as the side frame portions, as shown more clearly in Fig. 1. By adjusting the central threaded sleeve 35, the shoes 33 may be moved outwardly or inwardly. Thus, there is provided a ready means for adjustably supporting the door frame within the space between the walls which is to be filled with concrete. The adjustment means described are merely illustrative of various types of adjustable supports which may be employed for holding the door frames and window frames in the desired position within the space to be filled by concrete and against the pressure of the concrete or other material to be cast.

After the concrete, etc., has been poured into the space between the walls, and after the poured walls have cured, the C clamps 13, or other clamps employed, may be readily removed, and the forms stripped away. The bolts 28 may be retracted to separate the shoes 23 from the frame 26, and likewise the shoes 33 may be retracted and the forms may be lifted away. In the removal operation, the nuts of bolts 24 may be removed, and the forms 16 removed. The apparatus permits ready assembly and disassembly, and provides accurate means for adjusting the frame members within the wall opening so as to seal the space about the wall-opening frames. After the removal of the form apparatus, the frame will be embedded in the wall structure, as illustrated in Fig. 5.

It will be understood that in many cases, the window itself may be held in the form and abutting the window frame 26, and in this structure the members 20 and 23 would be omitted.

While in the foregoing specification, I have set forth specific apparatus in great detail for the purpose of illustrating an embodiment of the invention, it will be understood that such details of structure may be varied widely by those skilled in the art without departing from the spirit of my invention.

I claim:

1. In form apparatus useful for the casting of a wall about a wall-opening frame, a pair of panel walls spaced apart to receive cast material therebetween and enclosing the side walls of the wall-opening frame and providing further a channel extending inwardly of the frame, a form frame in said channel and fixed thereto, pressure shoes in said channel and adapted to bear against said wall-opening frame, and threaded rods extending through said fixed form frame and engaging said shoes to advance and retract them.

2. In form apparatus useful for the casting of a wall about a wall-opening frame, a pair of panel walls spaced apart to receive cast material therebetween and enclosing the side walls of the wall-opening frame and providing further a

channel extending inwardly of the frame, a form frame in said channel and fixed thereto, pressure shoes in said channel and adapted to bear against said wall-opening frame, said shoes and said wall frame being provided with interlocking surfaces to prevent relative movement of the shoes and wall-opening frame when the same are frictionally engaged, and threaded rods extending through said fixed form frame and engaging said shoes to advance and retract them.

3. In form apparatus useful for the casting of a wall about a wall-opening frame, said frame having a tongue extending inwardly therefrom, a pair of panel walls spaced apart to receive concrete therebetween and enclosing the side walls of said wall-opening frame, said panel walls having spaced flanges extended beyond said wall-opening frame to provide a channel therebeyond, a form frame in said channel, a bolt extending through the channel walls and said form frame to fix said frames to said channels, shoes mounted in said channel walls and having their inner surfaces provided with slots for receiving the tongue of said wall-opening, and threaded rods extending through said form frame and engaging said shoes to advance and retract them.

4. In combination with a pair of panel walls adapted to enclose a wall-opening frame and to receive concrete for the forming of a wall about said frame, said panel walls extending inwardly of said wall-opening frame to form a channel on the inner side thereof, a form frame between the said panel walls, means fixedly securing said form frame to said channel walls, and a shoe slideably guided by the said channel walls for movement toward and away from said wall-opening frame, and threaded means extending through said fixed form frame and engaging said shoe for advancing and retracting said shoe.

5. In combination with a pair of panel walls adapted to enclose a wall-opening frame and to receive concrete for the forming of a wall about said frame, said panel walls extending inwardly of said wall-opening frame to form a channel on the inner side thereof, a form frame between the said panel walls, means fixedly securing said form frame to said channel walls, and a shoe slideably guided by the said channel walls for movement toward and away from said wall-opening frame, and threaded means extending through said fixed form frame and engaging said shoe for advancing and retracting said shoe, said shoe and said wall-opening frame being provided with interlocking tongue and groove connections.

JOSEPH BANNEYER.
